UNITED STATES PATENT OFFICE

FREDERICK J. GREENE, OF RACINE, WISCONSIN, ASSIGNOR TO THE CHRISTENSEN MACHINE COMPANY, OF RACINE, WISCONSIN, A CORPORATION OF WISCONSIN

DELIVERY MECHANISM FOR SIGNATURE-STITCHING MACHINES

Application filed October 11, 1928. Serial No. 311,813.

This invention relates to certain new and useful improvements in signature stitching machines of that type illustrated in the Patent No. 1,750,622, issued to Elmer W. Bel-luche, March 18, 1930, and refers more particularly to the delivery mechanism thereof.

Heretofore, the length of signatures successfully handled by a stitching machine of the character described depended upon the overall length of its delivery mechanism and as it is sometimes desirable to stitch comparatively long signatures the size of the machine was necessarily larger than that required for the conventional run of work, thus increasing the initial and operating cost. Therefore, this invention has as an object the provision of a delivery mechanism for signature stitching machines and the like which is so constructed that the overall length of the delivery mechanism bears no relation to the length of signature the machine is capable of handling.

A further object of this invention resides in the provision of a delivery mechanism for signature stitching machines and the like which is of extremely compact construction and which has its driving elements so positioned as to leave its outer end open to permit signatures to extend therebeyond.

And a still further object of this invention resides in the provision of means for directing a signature past the end frame of the delivery mechanism.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a view of the delivery end of

a signature stitching machine embodying my invention, parts thereof being broken away;

Figure 2 is a view, partly in elevation and partly in section, taken through Figure 1 on the plane of line 2-2;

Figure 3 is a top plan view partly in section, of the delivery mechanism illustrating the saddle and signature guide and being taken through Figure 1 on the plane of line 3-3;

Figure 4 is a perspective view of the signature guide shown detached from the machine, and

Figure 5 is a fragmentary sectional view taken through Figure 3 on the plane of line 5-5.

Referring now more particularly to the accompanying drawings, in which like numerals designate like parts throughout the several views, 5 represents the main frame or base of a signature stitching machine, one end of which communicates with a signature conveyer or other like mechanism on which signatures are collected in groups and deposited on a substantially inverted V shaped saddle 6. The collected groups of signatures are then advanced along the saddle by other conveying mechanism, not shown, and presented to suitable stitching mechanism, not shown, mounted from an arm 7 carried by the main frame. After the groups have been stitched, the completed books are carried along the saddle 6 to the delivery end 8 of the stitcher, now about to be described, and ejected from the machine.

Inasmuch as the specific construction of the collecting, conveying and stitching mechanisms forms no part of the present invention they have not been illustrated, but reference may be had to Letters Patent Nos. 1,297,322 and 1,314,503 issued Martin Christensen for detail descriptions of typical constructions.

Standards 9 and 10 extending upwardly from the main frame 5 mount pairs of axially aligned bearings 11, 12 and 13 in which the adjacent ends of the shafts 14, 15 and 16 are respectively journaled, the outer end of shaft 14 being extended beyond the standard 10 to mount a pinion gear 17. As illus-

trated in Figure 2, the standard 10 is directed laterally, as at 18, to position its upper end carrying bearings 11, 12 and 13 beyond the end of the base 5 of the machine.

5 The shaft 14 is adapted to be oscillated for a purpose to be later described, by its pinion 17 with which a segment 19 meshes, the segment 19 having an arm 20 by which it is adjustably fixed to a substantially fork 10 shaped lever member 21 pivotally mounted on the adjacent end of the shaft 15. Rocking movement is imparted to the lever member 21 by a pitman or connecting rod 22, having one end connected with the lever member, as at 23, and having its other end connected with a crank pin 24 carried by a cam 25 fixed to a cam shaft 26 journaled in a suitable bearing carried by the frame 5.

20 The shaft 26 receives its drive from a motor, not shown, connected with a main drive pulley 27 by a belt or other means, not shown, the pulley being mounted on a drive shaft 28 transversely journaled in the frame 5 and connected with shaft 26 through spur gears 29 and spiral gears 30. Thus it will be seen that as the cam 25 rotates, segment 19 is rocked to oscillate the shaft 14.

25 Mounted upon the shaft 14 is a delivery roll or cylinder consisting of a plurality of 30 sidewise spaced discs 31, the peripheries of which have aligned recesses 32 through which a gripper finger operating shaft 33 extends, the shaft having its ends eccentrically journaled in the endmost discs. Gripper fingers 34 are suitably connected with the shaft 33, one adjacent each disc 31 and arranged to normally yieldably engage its outer free end with the periphery of its adjacent disc at one edge of the recess to grip 35 the completed groups of signatures 35 as they are inserted therebetween by a tucker blade 36. The tucker blade is actuated by suitable mechanism to project above the saddle apex at the moment the delivery roll is in its receiving position with its grippers in their open position to accomplish the insertion of the completed book on the saddle and over the blade, between the grippers.

40 The gripper fingers are actuated to their open position at the end of each oscillation of the delivery roll, by an arm 37 fixed to the shaft and carrying a roller which tracks on a cam 38 secured to the standard 10. The tucker blade 36 is normally held in its retracted position by a medially pivoted lever 39 actuated from a cam 40, which, when its depression passes under the cam follower of the arm 39, permits springs 41 to extend the blade above the apex of the saddle.

45 The specific manner in which the grippers 34 function is described in detail in the above referred to patent and is therefore not shown and described in detail.

50 As the delivery roll is oscillated in a forward direction, it carries a signature with

it, the signature free end being held substantially adjacent the delivery roll by a plurality of arcuate guards 31' suitably mounted from the main frame and disposed over and concentric with the delivery roll. At the completion of its forward oscillation, the delivery roll deposits the signature on fly sticks 42 which throw the same outwardly onto a delivery platform or table 43. The fly sticks 42 are positioned between adjacent discs 31 and have their lower ends secured in apertures formed in the shaft 16, their medial portions being bent, as at 44, to direct their outer arced end portions rearwardly to lie within the pockets or recesses of a substantially rake shaped cross bar 45, the ends of which are secured to the standards 9 and 10. The extreme outer ends of the fly sticks are directed upwardly, as at 46, to provide fingers which engage the edge of the deposited signatures to move them onto the platform 43 as the fly sticks are actuated by oscillation of the shaft 16.

55 Oscillation of the shaft 16 is produced from the cam 25, through a substantially triangular shaped bell crank or lever member 47 pivoted at its apex 48 to the base 5 and having a cam follower 49 which tracks on the face of the cam 25 to raise its outer end 50 at each passage of the high spot 51 of the cam. The end 50 of the member 47 is connected with an arm 52 fixed to the shaft 16 by means of a link 53 which passes through an opening 54 in the offset portion 18 of the standard 10, and a contractile spring 55 positioned within the interior of the base 5 and having its lower end secured to a fixed stud 56, and its upper end connected with a stud 57 carried by the lever member 47 and passed through an elongated aperture 58 formed in the wall of the base 5, yieldably maintains the follower 49 in engagement with the track of the cam 25 and retains the fly sticks in their retracted position.

60 To permit the signatures 35 to extend beyond the end of the delivery mechanism as illustrated in Figure 3 the standard 10 has its inner edge spaced forwardly of the center of the saddle 6 and the saddle plate 59 which forms one side of the saddle, is twisted to position its outer end substantially vertically and parallel with the inner edge of the standard 10. A signature guide 60 similarly twisted to follow the contour of the saddle plate is spaced therefrom to provide a passage through which the adjacent side of the signatures pass as they are conveyed along the saddle to their discharging position, arms 61 secured to the rake shaped cross bar 45 by screws 62, suitably supporting the same.

65 In this manner the signatures are readily guided past the standard 10 and the driving elements of the delivery mechanism which are so arranged as not to obstruct the path 130

of the signatures and permit the same to be extended outwardly of the end of the delivery mechanism so that the size of the signature which may be successfully handled is not contingent directly upon the length of the delivery mechanism.

The platform 43 is provided with intermittently movable belts or straps 63 trained about pulleys 64 mounted on the shaft 15 which is intermittently rotated by means of a ratchet device 65 suitably connected with the shaft 16 to be moved at each oscillation thereof.

I claim:

15 1. In a signature stitching machine or the like, a delivery mechanism including an end supporting member, a saddle along which signatures are conveyed to the delivery mechanism, and means for guiding the signatures past the end supporting member to permit them to extend therebeyond prior to being discharged from the machine by the delivery mechanism.

20 2. In a signature stitching machine or the like, a delivery mechanism including an end supporting member, a saddle along which signatures are conveyed to the delivery mechanism, and a guide member positioned adjacent the saddle for guiding the signatures past the end supporting member to permit them to extend therebeyond prior to being discharged from the machine by the delivery mechanism.

25 3. In a signature stitching machine or the like, a saddle member having a part disposed at an angle to the plane of its major portion and along which signatures are conveyed, and a guide member shaped to follow the contour of the saddle member and spaced therefrom to provide a passage through which the signatures pass.

40 4. In a delivery mechanism for stitching machines and the like, means for conveying signatures to the delivery mechanism, a support for the delivery mechanism, driving means for the mechanism, said support and driving means being so located with respect to the path of the signatures during their movement to the delivery mechanism that a signature may be extended beyond the support and past the driving means.

45 5. In a delivery mechanism for signature stitching machines and the like, means for conveying signatures to the delivery mechanism along a predetermined path, an end member supporting the mechanism, said end member being positioned to one side of the path of the signatures to permit the extension of a signature beyond the end member whereby a signature longer than the length of the delivery mechanism may be accommodated.

60 6. In a signature stitching machine or the like, a delivery mechanism including an end supporting member, means for conveying

signatures to the delivery mechanism, and means for guiding the signatures as they are conveyed past the end supporting member to permit them to extend therebeyond prior to being discharged from the machine by the delivery mechanism.

In testimony whereof I have hereunto affixed my signature.

FREDERICK J. GREENE.
